Lowell Manufacturing Company.
Letters Patent No. 1811-Dated Aug. 11th 1863.

The schedule referred to in these Letters Patent and making part of the same.

To all whom it may concern:

Be it known, that J. Elmer J. Key, of Lowell, in the County of Middlesex and State of Massachusetts, have originated and designed a new Pattern for Carpets or other fabrics, of which the following is a full, clear and exact description, reference being had to the accompanying drawings, making part of this specification.

A in the centre is an octagonal block around which are arranged four palm leaves each supporting a small rosette from which extend successions of broken leaves and sprigs.

By matching the four corners, a block is formed similar to A, with similar surroundings.

1, 2, 3, 4, are irregular mottled figures, the arms of which enclose the centre figures of the design, and also those of the corners when the design is matched.

Des. 1811

The colors employed for the different portions of the design may be varied to suit the taste and wish of the manufacturer.
